UNITED STATES PATENT OFFICE.

GEORGE STEINBERGER, OF CHERRYVALE, AND PAUL E. STEINBERGER, OF SYCAMORE, KANSAS.

AUTOMATIC WELL AND PIPE-LINE DRIP.

Application filed March 17, 1924. Serial No. 699,941.

To all whom it may concern:

Be it known that we, GEORGE STEINBERGER and PAUL E. STEINBERGER, citizens of the United States, and residents of Cherryvale, in the county of Montgomery, State of Kansas, and Sycamore, in the county of Montgomery and State of Kansas, respectively, have invented certain new and useful Improvements in Automatic Well and Pipe-
10 Line Drips, of which the following is a full, clear, and exact description.

Our invention relates to means for separating oil or water from the products of gas wells and the like, and has for its object
15 to provide a simple and inexpensive apparatus which may be employed at the well or at any point in the gas pipeline, and which will permit the separation of the liquid without wastage of gas.
20 Another object of the invention resides in the use of a novel form of gravity and float operated valve which is extremely sensitive.

A further object of the invention is the provision of resilient means for supporting the float so as to prevent a strain on the valve in the event that the weight of the float should become greater than normal, due to leakage or the absorption of water
25 or other liquid.

Other objects and advantages of the invention will be apparent from the following description when taken in connection with the accompanying drawings, in which:

30 Figure 1 is a side elevation of the main drip with our automatic drip connected therewith.

Figure 2 is a vertical section through the automatic drip and float.

35 Figures 3 and 4 are side and top views, respectively, of the valve.

Figure 5 is a vertical section through the valve, and

40 Figure 6 is a fragmentary section through the automatic drip taken at right angles to Figure 2.

45 Referring to the drawings more in detail, the numeral 1 indicates the main drip tank into which the products from the gas well or other source are conducted through the opening 2; the opening 3 being provided for the escape of the gas. Connected to the bottom of the main drip tank is a pipe 4 which

conducts off the oil, water and the like which enter the tank through the opening 2 with the gas. 55

Our invention relates to apparatus to be associated with the pipe 4 which will automatically discharge liquid received from the pipe 4, but which will prevent the escape 60 and wastage of the gas. To this end we have provided what may be termed an automatic drip to which the pipe 4 is connected. The drip includes a tank 5 which receives the pipe 4 at its upper end, and is 65 provided with a discharge conduit 6 adjacent its lower end.

Located at the bottom of the tank 5 and in the conduit 6 is a valve which comprises a body member 7 and a valve member 8 70 pivoted thereto, the pivot being indicated by numeral 9. The valve member 7 is provided with a passage 10 and has a ground valve seat 11 formed on its inner end. The inner portion of the body member 7 is 75 formed with the overhanging lug 12 for the reception of the hinge pintle 9, and is also provided with parallel side walls 13.

The valve member 8 is pivoted to the body member 7 through the medium of the pintle 80 9, and is formed with the spaced parallel flanges 14, between which is received the lug 12 and the parallel walls of the body member. A valve proper 15 is integrally formed on the member 8 between the flanges 14 and 85 11. By this construction of the walls 13 and flanges 14 it is obvious that the valve 15 will always be guided to its seat 11.

A float 16 is provided for automatically 90 opening the valve 15 from time to time; the float being connected to the valve member 8 by means of the rod 17. In order that no strain may be placed on the valve should the float leak, or absorb water in the case 95 of a wooden float, we have provided a coil spring 18 which is attached to the inner walls of the tank 5 just below the valve member 8. It will be readily understood that in the event that the weight of the float should be increased for any reason the strain on the valve parts will be relieved by the spring 18.

In operation the products of the gas well are received in the tank 1, the gas escaping 100 through the opening 3 and the liquid pass-

- ing down through pipe 4 into the automatic drip tank 5. When the liquid in the tank 5 reaches a predetermined level the float will rise to open the valve 15 and permit a portion of the liquid to escape or be forced out by the gas pressure. When the level of the liquid is lowered to its normal position the valve will again close and shut off further discharge from the tank.
- 10 While the automatic drip has been described solely in connection with oil wells, it is obvious that the apparatus may be placed in any gas pipeline in which it is desired to separate the liquid from the gas 15 without the escape of the latter.

From the foregoing description it will be seen that we have provided a simple and inexpensive apparatus for attachment to pipelines which may be readily placed in operation and one in which the valve is very responsive to the changes in liquid levels in the tank.

In accordance with the patent statutes, we have described what we now believe to be 25 the best embodiment of the invention, but we do not wish to be understood thereby as limiting ourselves or the scope of the invention, as many changes and modifications may be made without departing from the 30 spirit of the invention; all such we aim to include in the scope of the appended claims.

What we claim as new and desire to secure by Letters Patent is:

1. An automatic drip for gas wells and the like, including a tank, conduits leading 35 to and from the tank, a valve located in one of said conduits, an extension on said valve, a float attached to said extension, and a coil spring attached to the opposite walls on the interior of the tank and extending beneath 40 said float for supporting the same under certain conditions.

2. An automatic drip for gas wells and the like, including a tank, inlet and outlet conduits connected to the top and bottom of 45 the tank respectively, a body member provided with a ground valve seat attached to said outlet conduit and including flat parallel outer walls, a one-piece valve member pivoted to said body member above the seat 50 thereof and comprising spaced parallel flanges for cooperation with the flat parallel outer walls of the body member, a valve formed on said valve member between said parallel flanges and below said pivot point, said valve being formed with a ground 55 surface for cooperation with said ground valve seat, and a float for controlling said valve.

GEORGE STEINBERGER.
PAUL E. STEINBERGER.
